DESIGN FOR A CASING FOR A WOODWORK- ING MACHINE

Herbert E. Tautz, Milwaukee, Wisconsin, assign-
or to Delta Manufacturing Company, Milwau-
kee, Wis.

Application November 4, 1938, Serial No. 80,887

Term of patent 14 years

To all whom it may concern:

Be it known that I, Herbert E. Tautz, a citizen of the United States, residing at 620 East Vienna Avenue, in the city and county of Milwaukee and State of Wisconsin, have invented a new, original, and ornamental Design for a Casing for a Woodworking Machine, of which the following is a specification, reference being had to the accompanying drawing, forming part thereof.

Fig. 1 is a view in front perspective of a casing for a woodworking machine, showing my new design;

Fig. 2 is a view in rear perspective of said casing for a woodworking machine.

I claim:

The ornamental design for a casing for a wood-
working machine, as shown.

HERBERT E. TAUTZ.
